METHOD OF REFINING FATS AND OILS

Vernon Jersey, Cleveland, Ohio, assignor to S.
M. A. Corporation, Cleveland, Ohio, a corpora-
tion of Ohio

No Drawing. Application June 7, 1933,
Serial No. 674,777

5 Claims. (Cl. 87—12)

This invention relates to a method for removing free fatty acids from fats and oils containing valuable substances subject to destruction by oxidation or decomposition. More particularly, 5 the invention relates to a new and improved method for removing such fatty acids, either wholly or to such an extent that the proportion remaining is unobjectionable, from oleaginous materials containing carotene and/or other valuable fat-soluble pigments or pigment-like substances without deleteriously affecting these substances.

Certain oils are known to contain the hydrocarbon, carotene, which has important health-giving properties due to the fact that it is the 15 precursor of vitamin A and is converted into vitamin A in the liver. This valuable pigment is found in carrots, in the fats or oils pressed from the fruit of different varieties of palms, in oils extracted from sweet potatoes and from pumpkins, and in other sources. However, since the 20 proportion of carotene in these natural sources is rather low, in proportion to the amount of vehicle present, it is important to preserve as much of the carotene as possible. Furthermore, 25 the hydrocarbon, carotene, is very susceptible to oxidation, and serious losses in the amount of pigment realized in the finished product are experienced due to this oxidation. The same is 30 true of other natural pigments, such as the readily oxidizable xanthophyll, found in egg yolk oil, and the pigment lycopin, found in tomato pulp oil, since these pigments are, similarly to carotene, subject to partial destruction during 35 refining of the oils which contain them. A process by which the oil or fat, carrying these fat-soluble pigments, can be refined so as to remove objectionable ingredients, particularly free fatty acids, without destroying more than a minimum 40 amount of the pigments present, is needed and the present invention contemplates providing such a method.

It is, accordingly, an object of the present invention to provide a process of refining fats and 45 oils containing oxidizable pigment-like substances without harmfully affecting these substances. Another object of the invention is to provide a method of removing free fatty acids from fats or oils containing carotene without greatly reducing the proportion of carotene naturally present 50 in the fat or oil. Other objects of the invention will in part be obvious and will in part appear hereinafter.

It is known that free fatty acids, in particular, 55 are unpalatable in a fatty substance which is in-

tended to be taken into the alimentary tract and cause digestive disturbances when present in greater amounts than about 5%. Consequently, it has been attempted to remove these free fatty acids from oils containing carotene in order that 5 the oils might serve as a source of vitamin A in the human system. Such methods as have heretofore been used to effect this, have resulted in the destruction of a portion of the carotene content of the oil, so that a substantial amount of 10 the pigment is lost and exerts no therapeutic effect. In the present method, however, it is possible to conduct the purification so that substantially all of the readily oxidizable pigment will be 15 retained in the oil.

In accordance with the improved method, the oil obtained from a natural source, e. g., carrot oil expressed from air-dried carrot pulp, containing free fatty acids often in amount exceeding 5% of the oil, is treated with an aqueous solution of a soluble alkaline material, preferably 20 sodium hydroxide, although other alkalies, such as sodium carbonate, etc., may be used to neutralize these free acids. The alkali is added slowly to prevent rise of temperature, preferably 25 at such a rate that the heat of reaction is dissipated, as fast as generated, by the cooling water in the jacket or coils surrounding the reaction vessel. A temperature below 25° C. and, if conditions permit, nearer 20° C. is found to be most 30 desirable for fats that are liquid at this temperature; somewhat higher temperatures are required for fats having higher melting points, in order to maintain them in liquid condition. This comparatively low temperature, in most cases not far 35 removed from ordinary room temperature, prevents oxidation or decomposition of the pigment and also prevents emulsification of the oil with the soap which is formed by the neutralization. Of course, the temperature must be high enough 40 so that the fatty material does not solidify but remains liquid throughout the operation. Further to prevent emulsification, which would result in loss of some of the fat or oil, the necessary agitation to mix the alkali and fatty material is conducted slowly so as to produce a uniform distribution of the alkali, but not fast enough to produce any emulsification of the fat 45 with the soap. Such gentle stirring of the reaction mass also avoids incorporating air into the 50 fat, which would have a tendency to promote oxidation of the pigment.

After all of the alkali has been added, agitation is continued for about twenty minutes, or even longer, to permit completion of the reaction. 55

The amount of alkali added is closely regulated to correspond with the calculated or theoretical amount required to neutralize the determined free fatty acid content. An excess may be used, 5 say to the extent of 5 or 10%, but it has been found that an excess of alkali results in a lower yield of refined oil and also causes the destruction of some of the pigment which it is an object of the present method to preserve. Consequently, 10 a slight excess of alkali may be used to insure completion of the reaction, but such excess should be carefully controlled and preferably kept down to a minimum.

The concentration of alkali used to neutralize 15 the free fatty acids also has an important bearing on the preservation of the carotene or other valuable pigments present in the oil. Thus, when a very dilute alkali solution is used, containing a large amount of water, emulsions are formed 20 which are objectionable due to the difficulty of separating oil therefrom, and it is observed that this emulsification also results in destruction of color, i. e., pigment. This destruction of color results even when the amount of water used is 25 reduced to a point where emulsions do not readily form, for example when the alkali is added in a concentration of 10% (10 parts of alkali to 90 parts of water). However, the destruction of 30 pigment becomes less as the amount of water used to dissolve the alkali is reduced and this holds true up to a certain point, where another 35 phenomenon occurs, namely, failure of the soap to separate sharply from the fat after completion of the reaction; or in technical terms, the mixture fails to "break." This condition develops when the concentration of alkali in water is in the neighborhood of 50% and constitutes one 40 limitation on the strength of alkali which may be used. In general, it may be said that recovery of a refined oil of good color may be achieved by the use of alkali solutions containing even as little as 8% sodium hydroxide and from this 45 minimum strength up to concentrations in the neighborhood of a point where the soap and fatty material fail to "break." For best results with the least destruction of color, i. e., pigment material, an alkali solution containing 14-20% of sodium hydroxide should be used.

After completion of the neutralization, the 50 mixture of hydrolyzed fat and resulting soap is warmed to a temperature of 50-60° C., depending on the stability of the pigment or pigments or other easily oxidizable material present in the oil. At the same time, the agitator or other mixing means is stopped and the mass is permitted 55 to stand and separate into a clear upper layer of oil and a bottom layer of soap. When the mixture has thus stratified, the clear layer of oil may be decanted off, or the entire mass may be run off into a solid bowl centrifuge to effect 60 separation, or the mass may be clarified to separate the solid soap from the clear liquid fat. Any residue of soap remaining dissolved in the oil is removed by well known methods, as by 65 washing with water.

As a practical illustration, but in no sense of limitation, of the new process, the following is given: Carrot oil or other fatty material in the amount of 500 pounds is placed in a suitable tank and sodium hydroxide is run in to neutralize the free fatty acids. A titration indicates a fatty acid content of 6.5%, calculated as oleic acid, and the calculated amount of sodium hydroxide required to neutralize this proportion of free fatty acids in the entire batch is 4.6 pounds. 5.0 pounds 70

of sodium hydroxide having a purity of 97% (a small excess) is dissolved in 3 gallons of water and, after cooling, is slowly added to the fat which has previously been brought to a temperature of 20° C. The temperature is kept near this point 5 by means of cooling water in a coil or jacket surrounding the tank until neutralization has been completed. The contents of the tank are slowly agitated during the process until the same is completed, whereupon agitation is stopped and the 10 mixture is brought to a temperature of 50-60° C. Separation of oil and soap may then be carried out by any of the above mentioned procedures.

The method described in the foregoing example is applicable to fats or oils containing not over 15 about 10% of free fatty acids, although this value is not fixed, it being possible to treat fatty materials containing slightly greater amounts of the free acids, say 11 or 12%, in this manner. However, where the proportion of free fatty acids 20 present greatly exceeds this value, the procedure must be modified. Where the unrefined material contains up to 50% or more of free fatty acids, the large quantity of soap formed by the neutralization emulsifies the entire reaction mass and an 25 effective separation of soap solution and refined oil cannot be brought about. For this reason it is necessary to proceed by stages, adding in the first step only sufficient alkaline material to combine with about 10% of the oil as free fatty acid. 30 Upon neutralization of this amount, the resulting soap is separated from the oil and an additional 10%, or thereabout, of alkaline material, is mixed with the oil. After another separation of formed soap, a further neutralization is effected and this 35 procedure of alternate neutralization and separation is continued until all of the free fatty acids have been removed from the oil. In this way, the amount of soap present at any time is not sufficient to emulsify the oil and separation by 40 stratification or otherwise can be conducted. An oil containing 20 or 30% or more of free fatty acids can be neutralized by this procedure.

While it is known that readily oxidizable substances, such as plant pigments or vitamins, may 45 be protected from oxidation either by establishing a vacuum or by placing the material in an atmosphere of nitrogen or other inert gas, these expedients are not applicable to a process of refining oils. In the process of removing free fatty acids from an oil containing oxidizable substances, such as carotene, both the action of the air and the action of the alkaline solutions used for saponifying the free fatty acids must be 50 avoided as far as these deleteriously affect the 55 pigment. Since the establishment of such vacuum or inert atmosphere is not feasible from a practical standpoint, the present process operates in the presence of air but under conditions 60 that render the air practically harmless and the necessary alkali is used in such concentrations that no destructive action occurs. Excellent results are thus secured with a minimum of cost and without the installation of expensive gassing 65 equipment.

The method results in a product containing practically no free fatty acids, which are objectionable in an edible oil, and in which nearly all of the original pigment or vitamin content of 70 the oil or fat has been preserved despite the readily oxidizable nature of these pigments.

What I claim is:

1. The method of refining edible oils that are liquid at ordinary temperatures and which con- 75

tain appreciable amounts of carotene and a substantial amount but not more than approximately 10% of free fatty acids which comprises adding an aqueous solution of an alkaline material to the oil in the presence of air at substantially normal atmospheric pressure in an amount approximately just sufficient to combine with the free fatty acids present, slowly stirring the mixture to avoid inclusion of air, maintaining the temperature at about that of normal room temperature until neutralization is complete, warming the mixture to a temperature not greater than 60° C., allowing the mass to stratify and separating the refined product.

15 2. The method of refining edible oils that are liquid at ordinary temperatures and which contain appreciable amounts of carotene and a substantial amount but not more than approximately 10% of free fatty acids which comprises adding an aqueous solution of an alkaline material to the oil in the presence of air at substantially normal atmospheric pressure in an amount approximately just sufficient to neutralize all the free fatty acids present, gently mixing the ingredients of the mass to avoid aeration, maintaining the temperature at approximately 20° to 25° C. until neutralization is complete, warming the mixture to a temperature between approximately 50° and 60° C., allowing the mass to stratify and then separating the refined oil from the soap.

3. The method of refining edible oils that are liquid at ordinary temperatures and which contain appreciable amounts of carotene and a substantial amount but not more than approximately 10% of free fatty acids which comprises adding an aqueous alkaline solution containing about 8% to 20% alkali in an amount not greatly exceeding that necessary to neutralize the free fatty acids present, agitating the mixture in the presence of air at substantially normal atmospheric pressure so as to mix the ingredients while minimizing contact with air, maintaining the temperature at about 20° to 25° C. until neutralization is complete, warming the mixture to not

more than 60° C., allowing the mass to stratify and separating the carotene containing oil from the soap.

4. The method of refining palm oil which contains a substantial amount but not more than approximately 10% of free fatty acids while conserving its carotene content which comprises adding an aqueous alkaline solution of about 14% to 20% alkali in approximately the amount necessary to neutralize the free fatty acids present, 5 mixing the ingredients of the mass in the presence of air at substantially normal atmospheric pressure while minimizing the contact thereof with air, maintaining the temperature at about 20° to 25° C. until neutralization is complete, warming 10 the mixture to not more than 60° C., allowing the mass to stratify and separating the carotene containing oil from the soap.

5. The method of removing free fatty acids from oils that are liquid at ordinary temperatures 20 and which contain appreciable amounts of carotene and substantially more than 10% free fatty acids while conserving the carotene content which comprises adding an aqueous alkaline solution in sufficient amount to react with approximately 10% of the free fatty acids, mixing the ingredients in the presence of air at substantially normal atmospheric pressure while minimizing contact with the air, dissipating the heat of reaction as it is formed, heating the mixture after 25 the reaction is completed to a temperature not greater than 60° C., allowing the mass to stratify, separating the soap formed from the oil, mixing an additional alkaline solution with the oil in an amount sufficient to react with not more than 30 10% of the free fatty acids remaining, mixing the ingredients in the presence of air at normal atmospheric pressure while minimizing contact with the air, heating to a temperature of not 35 more than 60° C., allowing the mass to stratify, separating the soap and repeating the operation 40 if necessary until the oil is substantially free from fatty acids.
